US00D921947S

(12) **United States Design Patent** (10) **Patent No.:** **US D921,947 S**
Shan (45) **Date of Patent:** **** Jun. 8, 2021**

(54) **SEARCH DIRECT CHARGE LED FLASHLIGHT**

(71) Applicant: **Jian Shan**, Lincoln, NE (US)

(72) Inventor: **Jian Shan**, Lincoln, NE (US)

(**) Term: **15 Years**

(21) Appl. No.: **29/679,677**

(22) Filed: **Feb. 8, 2019**

(51) **LOC (13) Cl.** **26-02**

(52) **U.S. Cl.**

USPC **D26/49**

(58) **Field of Classification Search**

USPC D26/37-38, 40-42, 46, 49-50

CPC F21L 2003/00; F21L 4/00; F21L 4/005;

Primary Examiner — Brandon M Rosati

(57) **CLAIM**

I claim the ornamental design for a search direct charge LED flashlight, as shown and described.

DESCRIPTION

FIG. 1 is a top rear perspective view of a search direct charge LED flashlight according to the new design;

FIG. 2 is a bottom front perspective view of the search direct charge LED flashlight illustrated in FIG. 1;

FIG. 3 is a bottom rear perspective view of the search direct charge LED flashlight illustrated in FIG. 1;

FIG. 4 is a top front perspective view of the search direct charge LED flashlight illustrated in FIG. 1;

FIG. 5 is a rear side elevational view of the search direct charge LED flashlight illustrated in FIG. 1;

FIG. 6 is a left side elevational view of the search direct charge LED flashlight illustrated in FIG. 1;

FIG. 7 is a front side elevational view of the search direct charge LED flashlight illustrated in FIG. 1; and,

FIG. 8 is a right side elevational view of the search direct charge LED flashlight illustrated in FIG. 1.

1 Claim, 8 Drawing Sheets
